MAYS ACCOUNTING MACHINE COMPANY, OF ASHEVILLE, NORTH CAROLINA, A
CORPORATION OF NEVADA.

COMBINED TYPE-WRITER AND CALCULATOR.

1,127,060.

Specification of Letters Patent.

Patented Feb. 2, 1915.

Application filed April 6, 1912. Serial No. 688,913.

To all whom it may concern:

Be it known that I, JAMES F. MAYS, a citizen of the United States of America, residing at Birmingham, in the county of 5 Jefferson and State of Alabama, have invented certain new and useful Improvements in a Combined Type-Writer and Calculator, of which the following is a specification.

10 My invention relates to an improvement in combined typewriting and calculating machines so designed that either machine may be used independently and yet both may be readily assembled and connected up 15 for joint operation so that the manipulation of the keyboard of the calculating machine will operate the numeral keys of the typewriter to print the numerals of a number which is set up by the adding mechanism on 20 its accumulator dials.

One important object of my invention is to provide a light and inexpensive attachment for a standard typewriter by means of which it is adapted for the joint use described with a calculating mechanism and which does not interfere with the normal use of the typewriter and may be readily attached to and detached from the typewriter.

30 Another important feature of my invention, which I consider fundamentally novel, is adapting the combined mechanisms to serve every purpose required of a billing machine, my invention being adapted to 35 produce a typewritten itemized bill, to carry the totals of the items of the bill, to calculate the results representing the several items of the bill, and to exhibit the final total on the totaling dials of the calculator 40 for transcription, all these operations being obtained by a coordinated operation of the typewriter digit keys, and the keys of a calculating machine having independent sets of dials, one set for totals and the other 45 for calculations.

A further object of my invention is to provide a means controlled preferably by one operation of a lever or key to throw the calculating mechanism into connection with 50 the typewriter operating mechanism and the set of totaling dials, and by a reverse operation of said key or lever to connect the calcu-

lating mechanism only with the set of calculating dials.

I do not claim in this application separately the calculating mechanism with its independent sets of accumulating and calculating dials, as the same forms the subject matter of a separate application to be filed of even date herewith.

60 My invention further comprises the details of construction and arrangement of parts which are hereinafter more particularly described in their preferred embodiment only, reference being had to the accompanying drawings, in which:—

Figure 1 illustrates a top plan view of the typewriter and calculator assembled for joint operation and broken away in parts to illustrate the operating mechanism in plan 70 view. Fig. 2 is a front elevation of both typewriter and calculating machine coupled together and broken away to illustrate the operating mechanism in elevation. Fig. 3 is a side elevation of the typewriter and its 75 attachment in assembled position, the rock shafts being shown in cross section. Fig. 4 is a side elevation of the calculating machine broken away in parts to indicate the two sets of dials and the lever shift means for coupling one or the other sets of dials with the key controlled mechanism.

Similar reference numerals refer to similar parts throughout the drawings.

I have illustrated my invention in connection with a standard form of typewriter, but it may obviously be used with other types than that shown. In like manner I have selected a calculating machine wherein the depressible keys 1 depress spring supported shanks 2 which carry pins 3 for engagement with crank arms 4 on rocker shafts 5 which extend from front to rear of the machine and have squared ends 6 at their forward ends and squared ends 7 at their rear ends. The shanks 2 continue below the arms 4 and are adapted each to engage a pin arm 8, a series of which project from each transverse rocker shaft 9. There are nine of these rocker shafts disposed at the bottom of the calculator casing 10 and each is journaled in lugs 11 which are stamped and bent at right angles to the shaft supporting angle plates 12 which are suitably

connected to the bottom of the casing 10, there being preferably one such plate for each rocker shaft 9. As seen in Fig. 2, the front transverse rows of keys of the calculator machine which bear the numeral 1 will operate the front shaft 9, the row of keys designated 2 will operate the second shaft and so on throughout the series, all calculator keys of the same denomination of 5 numeral figures being adapted to operate the same shaft 9. Couplings 13 are slidably mounted on the squared ends of shafts 5. I mount similar couplings on the left hand ends of the shafts 9 which are likewise 10 squared. These several couplings are provided with a circumferential groove to receive coupling shift bars, there being a common shift bar 14 for the front couplings on the shafts 5 and a shift bar 15 for the rear couplings on the shafts 5, and a shift bar 16 for the couplings on the shafts 9. The several shift bars are alike in construction and are formed by an angle plate which is notched at intervals so that it will have 15 a slip fit in the grooves in the couplings after the fashion of a yoke to permit the couplings to turn freely. Each of the shift bars 14 and 15 have their ends bent at right angles and connected by screws to connecting bars 17, one of which bars is connected to an intermediate point of the shift controller lever 18 which is pivoted in a bearing 19 at the bottom of the casing 10 and projects through a top opening in the casing 20 preferably at the right hand side thereof. As the lever 18 is moved toward the rear, both shift bars 14 and 15 are moved rearwardly with it. This will cause the forward couplings 13 to become disengaged 25 from the squared ends of the alining shafts 19 which transmit movement, when coupled to the key operated shafts, to the mechanism (not shown) for operating the forward accumulating or total dials 20 which 30 carry numerals that are exposed through suitable top openings at the front end of the calculator casing. The same movement of the lever 18 throws the rear couplings 13 into engagement with the squared ends of shafts 21, which operate the mechanism (not shown) for moving the rear or calculating dials 22. This operating mechanism for the 35 dials may be of any suitable type such as that shown in my Letters Patent No. 842,682, or in my application of even date herewith. The couplings 13 have squared openings which enable them to readily act to connect the several key controlled rock shafts 5 with either of their respective alining shafts 19 or 21, according to the position of the lever 18. The left hand connecting bar 17 (Fig. 40 2) carries a pair of crank pins 23 mounted on plates 24 bolted or riveted to the bar, and each pin is adapted to engage in a slot in the bifurcated end of a horizontally 45

movable crank arm 25 connected to a vertically disposed pivoted member 26 which is mounted in suitable bearings attached to the side of the casing 10 and has at its lower end a horizontally moving crank arm 27 pivotally connected to a link 28 which in turn is connected by a pivot pin or screw to the shift bar 16 for the several couplings on the shafts 9. In Fig. 1 the arms 24 are disposed above the angled end of plates 24 which support the pins 23, while in Fig. 2, the plates 24 are above the crank arms 27 and have the pins depending. Either arrangement may be used according to the available space in the casing 10. As the connecting rod 17 is shifted to the rear (Fig. 1) the pins 23 swing the crank arms 27 toward the rear, which movement, by means of the links 28, will draw the shift bar 16 to the left and move the couplings 13 on the transverse rock shafts 9 until their squared outer ends engage the squared ends 29 of a series of nine horizontal rock shafts 30, carried by the typewriter attachment, and couple each of them to its respective alining shaft 9.

The typewriter frame 32 rests on its cushion feet 33 and has connected to it a plate 31, bent up at each side and provided with inturned flanges 34 and vertical flanges 35, the flanges 34 and 35 being adapted to receive between them the bottom edge of the side bar 36 of the typewriter frame and to be locked in engagement therewith by a clip 37 which hooks over the top of bar 36 and is connected by a screw 38 to the flange 35. Also set screws 39 in the flanges 34 serve to make the connection of the attachment more rigid to the typewriter frame. The plate is thus suspended from the typewriter frame as an attachment which does not in any manner interfere with the ordinary use of the machine and leaves it free to be moved about at will. The shafts 30 at one end are journaled in the upturned end wall of the frame 31 and are supported at their inner ends in bearings 40 formed by angle plates attached to plate 31. As there are nine of these shafts 30, there will be nine of these bearing plates 40, and to make the frame 31 more rigid, I bend it to provide a longitudinal rib 41 between the bearing supports for each shaft 30. Along the rear edge of plate 31 I mount a series of nine standards 42 formed by vertical plates which carry at their upper ends studs 43 on each of which a bell crank lever 44 is pivotally mounted. The plates are disposed so that said levers will stand under the nine digit keys 45 of the typewriter. As my preferred means of connecting each lever 44 to a key 45, I slip a bent metal clip 46 over each digit key 45 and connect the lower ends of the clip by a pin 47 to a link 48 with an elongated slot 49 in which engages a pin 50.

on the upper end of the adjacent bell crank lever. The lower ends of these levers are each connected by a rod 51 with a crank arm 52 rigidly attached to one of the shafts 30. Each shaft 30, which operates a given numeral key, is adapted to be connected up with a shaft 9 which is movable by the several calculator keys having the corresponding designating numeral. The slots 49 leave the typewriter numeral keys free for direct manipulation, and yet, through the connections described, the typewriter numeral key will be depressed by the manipulation of the corresponding calculator keys, when the typewriter and adding machine are connected for joint manipulation. As I prefer to inclose all the calculating mechanism within the casing 10, I provide openings in its side wall for the shafts 30, which openings effectively align said shafts with shafts 9. The calculator is provided with any suitable type of mechanism, controlled by keys 55, to clear the dials 22 and 20 respectively. The keys 56 are to prevent the carrying process from dial to dial. To insure the ready and proper connection of the typewriter and adding machine, after the shafts 30 have been passed through suitably spaced openings in casing 10, I provide lugs on the casing 10 which may be long, as lugs 54 in Fig. 1, or shorter, as lugs 53 in Fig. 2. Each lug 53 or 54 is adapted to overlap the end of the flange 35 and be fastened thereto by a pin or screw 55^a which may be readily removed to unlock the machines.

To illustrate the operation of my invention, as a complete billing machine, we will assume that the bill head has been inserted in the typewriter, properly addressed, and the first item to be written out is, say, 144 yds.—120 yds.—129 yds.=393 $\frac{1}{4}$ yds. @ .08 =\\$31.46. The numbers 144, 120 and 129 are struck upon the typewriter keys and the lever 18 is drawn forward to couple the calculator mechanism with the front dials and disconnect it from the rear dials and the typewriter attachment. The total of the yardage is then added up on the front dials 20 of the adding machine and the total is struck by the typewriter keys. Then this total yardage is multiplied on the same front dials and when the product is obtained, the lever 18 is pushed to the rear so that the adding mechanism is uncoupled from dials 20 and coupled to the rear adding dials 22 and to the typewriter attachment, and the result is struck on the adding machine keys, which operation prints the total figures in the bill and at the same time places the total amount upon the rear accumulator dials 22. By this method the calculations are sure to be correct, and at the end of a bill the grand total is shown upon the rear accumulator dials and is then struck by the typewriter keys on the bill. Thus the total of the bill

when finished, can be checked with the total shown upon the rear accumulators.

Either machine can be readily detached and separately used or quickly assembled for joint use. All of the advantages of joint operation which are described in my pending application, Serial No. 311,006, can be obtained by my present invention, and in addition thereto, the separate item calculations can be performed mechanically without disturbing the setting up of totals on the total dials.

Having thus described my invention, what I claim as new and desire to secure by Letters Patent, is:

1. A calculator having a keyboard, two independent sets of accumulator dials, mechanism operated by the keyboard, and selective means to connect said mechanism with either one of said sets of dials and disconnect it from the other, in combination with a typewriter, mechanism for operating the digit keys of the typewriter, and means to interconnect said mechanism operated by the calculator keyboard with said mechanism for operating the digit keys and to disconnect said mechanisms from each other, whereby one set of said dials may be operated from the calculator keyboard independently of the typewriter, and the other set operated from said keyboard in conjunction with said typewriter.

2. A calculating machine having two independent sets of accumulator dials, a common keyboard and key controlled operating mechanism for said dials, a typewriter having operating keys, connecting devices compelling the manual operation of corresponding keys of the typewriter and calculating mechanism, and mechanism to render one set of dials operative from the calculating machine keyboard independently of the typewriter and the other set operative in conjunction with said typewriter.

3. In combination, adding mechanism having two independent sets of adding dials, a typewriter having manual keys, connecting devices to cause the operation of the adding mechanism to simultaneously act on one set of dials and on the numeral keys of the typewriter, and means to throw said adding mechanism into operative connection only with the other set of dials.

4. The combination with an adding machine having a set of calculating dials and an independent set of totaling dials and a common key controlled actuating means for operating either set of dials, of a typewriter having numeral keys, means to effect the operation of said numeral keys by the correspondingly numbered adding machine keys, and means to disconnect the typewriter and the calculator dials from said actuating means when the latter is operably connected with the totaling dials, substantially as described.

5. In combination, adding mechanism comprising numeral keys, two sets of dials, and means to operate said sets of dials independently by said keys, a typewriter having numeral keys, connecting devices to compel the manipulation of the adding mechanism keys to move corresponding typewriter numeral keys, and means to simultaneously disconnect the typewriter keys and one set of dials from the numeral keys of the adding mechanism.

6. In combination, adding mechanism comprising numeral keys, two sets of dials, and means to operate said sets of dials independently by said keys, a typewriter having numeral keys, connecting devices to compel the manipulation of the adding mechanism keys to move corresponding typewriter numeral keys, and means to simultaneously disconnect the typewriter keys and one set of dials from the adding mechanism and throw the other set of dials into operative relationship with the adding mechanism.

25 7. A typewriter attachment comprising a frame adapted to be connected to a typewriter, actuators on said frame adapted to be connected each to a digit key of the typewriter, which keys, when directly manipulated, will move independently of said actuators, and calculating mechanism comprising rock shafts and means to couple said shafts with said actuators to manipulate said digit keys.

35 8. A typewriter having digit keys, in combination with a hanger detachably connected to said typewriter, a series of rock shafts journaled in said frame, means connecting each shaft to a digit key, a calculating machine and means to detachably connect each rock shaft to the manipulative parts of said calculating machine.

45 9. A typewriter, a hanger detachably connected thereto, a series of rock shafts journaled in said hanger, means connecting each shaft to a digit key, and means to detachably connect each rock shaft to the manipulative parts of a calculating machine which respond to the movement of keys bearing 50 the same number as the respective digit key which said actuator is adapted to operate.

10. In combination, a typewriter having numeral keys and transversely disposed attachments having lost-motion connections 55 with the said numeral keys for operating them while leaving the keys free for direct manipulation, a calculator having laterally disposed members which move responsive to the manipulation of the calculator keys, means to connect the typewriter and calculator in position side by side, and means to couple the oppositely disposed and corresponding calculator members and typewriter key operating attachments.

11. The combination of an adding machine, numeral keys, key controlled dial operating mechanism, a series of transverse rock shafts below the dial operating mechanism, the operation of said keys being adapted to both actuate said dial operating mechanism and to rock their respective transverse shafts, a typewriter having numeral keys, transverse rock shafts disposed below said keys and operatively connected thereto, and means to couple up the two sets 75 of transverse rock shafts, substantially as described.

12. A typewriter attachment comprising a frame of substantially the same width as the typewriter, clips for attaching it to the typewriter, and mechanism on the frame which is adapted to operate the keys of a typewriter and which yet leave the typewriter independent thereof for direct manipulation, said mechanism comprising rock 85 shafts which are laterally disposed and adapted for detachable connection to a calculating machine.

13. A typewriting machine comprising 90 numeral keys, a separate calculating machine comprising key controlled adding devices, means to detachably connect said separate machines in predetermined relationship, and laterally projecting mechanism carried partly by each machine and forming 95 an attachment thereto, and adapted to be coupled up, said mechanism acting to operate a typewriter numeral key when a correspondingly numbered key of the adding machine is manipulated.

100 14. The combination with a typewriter and its numeral keys, of an attachment comprising a series of nine rock shafts, a lost-motion connection from each rock shaft to a numeral key, said lost-motion devices permitting the keys to be depressed independently of their actuators which are adapted to be operated by the mechanism of an adding machine, an adding machine, rock shafts which move responsive to the manipulation 110 of the adding machine keys, and slip couplings to connect each adding machine rock shaft with a rock shaft of the typewriter attachment, substantially as described.

115 15. A typewriter attachment comprising a support, a series of transverse rocker shafts journaled thereon, means including a plurality of rocker shafts to connect the first mentioned rocker shafts respectively with the numeral keys of the typewriter, 120 and means to suspend said support beneath the typewriter, substantially as described.

16. A typewriter attachment comprising a support, a series of transverse rocker shafts journaled thereon, numeral keys of the typewriter, levers mounted on said support, an arm on each rocker shaft, means to connect each arm to a crank, and a lost-

- motion connection between each crank and a numeral key to permit said keys to be manually operated independently of said actuators, in combination with a calculator 5 having laterally projecting rock shafts, each adapted to be operated by a key or keys of a given denomination, and means to couple each such calculator rock shaft to the typewriter rock shaft adapted to operate the 10 typewriter numeral key of the corresponding denomination, substantially as described.
17. In a calculating machine, a key board, key controlled calculating devices, a series of transverse key operated rock shafts, couplings on corresponding ends of said shafts, alining shafts operatively connected to the numeral keys of a typewriter, and means to simultaneously move said couplings to connect or disconnect said alining shafts, as 20 and for the purposes described.
18. The combination with a typewriter having an attachment comprising a series of nine shafts and connections from each shaft to a numeral key of the typewriter, of 25 a juxtaposed adding machine having a supplemental series of nine transverse rocker shafts, said two series of shafts being adapted to be brought into alinement, a series of couplings to connect the alining 30 shafts, a lever in said adding machine, and mechanism movable thereby to simultaneously couple and uncouple said alining shafts.
19. In an adding machine, a keyboard, 35 two independent sets of dials, key controlled dial operating mechanism comprising a set of rocker shafts, means to connect said rocker shafts with one or the other set of disks, a supplemental set of transverse rock
- shafts, means to couple said supplemental 40 shafts to actuators for operating numeral keys for typewriter, and means to simultaneously connect said actuators and one set of dials to rocker shafts of the adding machine and to disconnect the other set of dials 45 therefrom, substantially as described.
20. The combination with a typewriter having numeral keys, of a calculator having key controlled mechanism, transmission means to operatively connect each typewriter numeral key with the calculator parts movable by the correspondingly numbered key or keys thereof, a coupling interposed in said transmission, and a shift key adapted to control said coupling to connect or disconnect said numeral keys from the calculator, substantially as described.
21. In combination, a typewriter machine having numeral keys, a calculating machine having two sets of dials, and a key controlled 60 mechanism adapted to actuate one or the other of said sets of dials at a time, motion transmission means adapted to depress a typewriter numeral key responsive to the depression of a calculator key of the same 65 denomination, and key controlled means which interrupts the operative connection between the calculator keys and a given set of dials and also between the calculator keys and said typewriter numeral keys. 70

In testimony whereof I affix my signature in presence of two witnesses.

JAMES F. MAYS.
